UNITED STATES PATENT OFFICE.

JOHN BRIGGS, OF LOUISVILLE, KENTUCKY, ASSIGNOR TO HIMSELF AND J. J. HAIR, OF SAME PLACE.

IMPROVEMENT IN TOBACCO-PRESSES.

Specification forming part of Letters Patent No. 36,751, dated October 21, 1862.

To all whom it may concern:

Be it known that I, JOHN BRIGGS, of Louisville, in the county of Jefferson and State of Kentucky, have invented a new and Improved Implement or Device for Compressing Tobacco; and I do hereby declare that the following is a full, clear, and exact description of the same, reference being had to the accompanying drawings, making a part of this specification, in which—

Figure 1 is a side view of my invention; Fig. 2, an end view of the same.

Similar letters of reference indicate corresponding parts in the two figures.

This invention relates to a new and improved implement or device for compressing tobacco plugs or rolls for boxing.

The object of the invention is to obtain a simple implement for the purpose—one that may be much more readily manipulated than those hitherto arranged, and far more durable or less liable to break.

To enable those skilled in the art to fully understand and construct my invention, I will proceed to describe it.

A represents what may be termed the "body" or "main portion" of the device, which is constructed of wood, and of scroll form in its transverse section—that is to say, it departs from a true cylinder by a regular spiral curve sufficiently to form a shoulder or ledge, *a*, the whole length of A. Through the center of A there is a square opening, *b*, which may be lined with metal plates, and the exterior of A is also covered with metal, *c*. Heavy sheet-iron will answer the purpose. The body A is provided with a door, B, formed by detaching by radial cuts a longitudinal section from A, the cuts extending to two corners of the opening *b*, so that one side of said opening will be formed by the door, as clearly shown in Fig. 2. This door is hung to the body A by strong hinges *d d* at the side opposite to that where the shoulder or ledge *a* is formed. The body A is encompassed by two strong metal bands, *e e*, and the hinges *d d* are formed in these bands, the latter extending over the door B, and reaching nearly to the shoulder *a*. The ends of the bands *e e* on the door have rods fitted in them, or one rod, *f*, may be fitted in both, and said bands are slotted near the rod *f*, as shown at *g*, in order to

expose a portion of the rods, as shown clearly in Fig. 1.

C represents a curved metal bar, which is forked or divaricated at one end. The arms *h h* of this bar C are connected to links *D D*, and these links are attached to the ends of the bands *e e* which are at the outer edge of the shoulder or ledge *a*. The pin *i*, which connects the arms *h h* to the links *D*, extends from one link to the other, as shown in Fig. 1, and the ends of the arms *h h* are provided with notched projections *j j*, as shown in Fig. 2, to fit in slots *g* and against the rod *f* in the ends of the bands *e e* on the door B. The outer end of the bar C has a hole or opening, *k*, made through it to admit of a rod, E, being passed through. This rod is bent or curved at one end in the form of a hook, *E'*, and said hook is fitted in a link, F, which is attached to or passes through the ends of two bars, *ll*, the opposite ends of said bars being attached one to each bar *e*. The opposite or outer end of the rod E has a screw-thread, *m*, cut on it to receive a nut, G, which is provided with a handle or crank, H.

From the above description it will be seen that the links *D D* form what may be termed "double joints" or "hinges" for the arms *h h* of the bar C, and admit of the notched projections *j j* being fitted on or against and withdrawn from the rod *f*; and it will also be seen that the arms *h h* are bent levers, which, when the outer and free end of the bar C is forced toward the body A under the action of the nut G, will press the door B inward and compress the tobacco in the opening *b*. In thus actuating the bar C to obtain the pressure the strain of said bar is brought to bear at two opposite points on the bands *e e* of the body A, and the latter is well calculated to resist the strain, as the bands *e e* serve as loops, and effectually prevent the rupturing of the body. After the compressing operation is effected the nut G is unscrewed, so as to loosen the bar C, and the notched projections *j j* are removed from the rods *f* and the door B, so that the compressed tobacco may be taken from *b* and replaced by other tobacco, which is acted upon in the same way.

The device is extremely simple, may be manipulated with the greatest facility, and constructed at a small cost.

Having thus described my invention what I claim as new, and desire to secure by Letters Patent, is—

1. The box or body A, constructed of spiral or scroll form in its transverse section, so as to form a ledge or shoulder, a, and provided with a door, B, in combination with the bar or lever C, screw-rod E, and nut G, all arranged as and for the purpose herein set forth.

2. The manner of applying the lever C and the screw-rod E to the box or body A—to wit, by means of the links or double joints D D, the link F, bars *ll*, and bands *ee*, as described.

JOHN BRIGGS.
